UNITED STATES PATENT OFFICE.

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS.

WRINGER-POSITION-CONTROLLING MEANS.

Application filed April 30, 1923. Serial No. 635,509.

To all whom it may concern:

Be it known that I, ALPHEUS W. ALTORFER, a citizen of the United States, and a resident of Peoria, in the county of Peoria and 5 State of Illinois, have invented new and useful Improvements in Wringer-Position-Controlling Means, of which the following is a specification.

This invention has reference to wringer 10 position controlling means for power operated washing machines.

Practically all power operated washing machines are equipped with power operated wringers, the wringers receiving their power 15 through vertically disposed shafts actuated from the same motive means employed to actuate the washing element or elements. Furthermore, such wringers include a frame swingably mounted at the upper end of the 20 vertical shaft to be swung there-about into different positions, for wringing from the washing machine into rinse, or blueing water, and finally into a basket or other receptacle. Some means are provided to lock or 25 hold the wringer frame in different adjusted positions relative to the washing machine. Under ordinary conditions, with the wringer rolls running freely or under light load the torque applied to the vertical shaft will not 30 have a tendency to affect the wringer frame, but when the wringer rolls are under heavy load the resistance will tend to impart the torque of the shaft to the wringer frame, and unless provision is made to hold the frame 35 against swinging movement in the direction of the torque imparted to the frame by the shaft, said frame will have a tendency to turn resulting in possible danger to the attendant.

40 My controlling means is aimed to and does obviate this danger, and will automatically lock the wringer frame against movement in the direction of the torque while permitting a free swinging movement in the opposite direction. Furthermore, the locking means is arranged for free manual manipulation, without the use of tools to permit free swinging movement of the wringer frame in either direction, at the will of the attendant, and such locking or adjusting means includes means adapted for free manual manipulation, without the use of tools to lock the wringer frame, when adjusted, against movement in either direction.

The invention further comprehends a plurality of selective positions to which the wringer frame may be adjusted and held, instead of only two or three usual in machines of this character.

That the invention may be more fully understood, reference is had to the accompanying drawings, forming part of this application, illustrating a preferred embodiment of the invention, in which:

Figure 1 is a side elevation of so much 65 of a wringer support and wringer frame as will illustrate the application of my invention thereto;

Figure 2 is a detail side elevation looking in at Figure 1, on the line 2—2;

Figure 3 is a detail section in plan on the line 3—3 Figure 2;

Figure 4 is a plan view, partly in section, of the mechanism shown in Figure 3;

Figure 5 is a side elevation showing the 75 relation of the wringer frame to the washing machine, both shown in dotted lines, with certain locking elements removed;

Figure 6 is an enlarged detail sectional view showing how the wringer frame is supported for swinging movement and elements of the locking means;

Figure 7 is a cross-section, in plan, on the line 7—7 Figure 6, and

Figure 8 is a cross-section, in plan, on the line 8—8 Figure 6.

Like characters of reference denote corresponding parts throughout the figures.

For convenience the washing machine, only a part of which is shown, is designated 1 90 and the wringer frame 2. The latter is of the usual construction, including wringer rolls which are operated through clutch controlled gearing, not shown, from a vertically disposed shaft 3 arranged to be operated 95 from the same motive power employed to operate the washing element or elements of the washing machine.

The frame 2, as is customary in machines of this character, is swingably supported at 100 the upper end of a preferably tubular support, standard or casing 4 secured in an upstanding position on the frame of the machine 1 and in which is journaled the shaft 3.

At or near the top of the support 4 and 105 arranged externally thereof, is a flanged member 5 provided with a ratchet-toothed periphery 6, the shoulder of each tooth be-

- ing disposed radially of the support. I show a multiplicity of such teeth so as to provide a plurality of adjustable positions for the wringer frame about the support 4.
- 5 The wringer frame 2 is provided with a depending tubular casing or sleeve 7 adapted to fit and have a removable telescopic relation with the upper end of the support 4, and in which or on which it is swingable; 10 the shaft 3 passes up therethrough to the reverse gearing for the wringer rolls. To said casing or sleeve is connected a housing 8, formed preferably, by a depending annular flange 9 which embraces and surrounds the 15 ratchet-toothed member 5, when the wringer frame is in position on its support, and when in such position the housing rests and rotates on the upper end of the support 4. Said housing is further provided with an 20 off-set chambered portion 10, and the flanged wall 9 of said housing is provided with an opening 11 therethrough, of suitable width. Within the chamber 10 of the housing 8 is pivoted an arm 12 having a finger engaging 25 portion 13 which projects through and may have oscillatory movement in the opening 11. Said arm has a tooth 14 adapted to ride over the teeth of the ratchet member 5, as the frame 2 is swung about its support, in one 30 direction, and to engage the radial faces of such teeth to hold the frame against movement in the other direction. The arm 12 and its tooth 14 constitutes a pawl pivoted within the housing and having a protruding finger- 35 hold for the free manipulation of said pawl by an attendant, without the use of tools, to release said pawl to permit swinging movement of the wringer frame, in either direction, at the will of the operator.
- 40 Said pawl is yieldingly held in ratchet tooth engagement, and is returned to such position, when released, by a spring 15, preferably arranged, as shown in Figures 3, 6 and 8. The housing 8 is secured in position 45 on the casing or sleeve 7, by means of a hub 16 embracing said casing or sleeve held by set screws 17 threaded through the wall of said hub and entering openings 18 in the said casing or sleeve.
- 50 The parts being arranged and assembled, as shown, the wringer frame may be swung on its support without vertical movement of the housing on the wringer frame and without vertical movement of the ratchet-toothed 55 member on the support for the wringer frame. And by locating the pawl on the swingable wringer frame in the position shown it will be observed that it always assumes its natural position with said 60 frame as it is swung. This makes for ease and convenience of control of the pawl in whatever position the frame may be in and the attendant is not required to reach around or over obstructions to get to the 65 finger-hold 13 in the event of it being de-

sirable to use it to release the pawl from the ratchet-toothed member, to swing the frame in the direction against which it may be locked.

From the foregoing it is apparent that 70 the wringer frame is automatically locked against swinging movement in the direction of the torque imparted to the wringer frame from the shaft and that it is free to be swung in the opposite direction. Also, that the 75 locking means may be freely manipulated by the attendant, without the use of tools, to permit swinging movement of the frame in either direction, at the will of the operator. In addition to such an arrangement I have 80 provided a means for locking the wringer frame, after adjustment, in either direction. Such means comprises a locking pawl 19 pivoted to the finger-hold 13 and located without the housing 8 and having a locking 85 portion 20 swingable into and out of the opening 11 in the housing, and when located within said opening locking against one of the end walls of said opening. When the pawl 19 is in locking position, see Figure 3, 90 the tooth 14 will hold the frame against swinging movement in one direction, and the locking portion 20 of the pawl 19 will hold said frame against swinging movement in the other direction. The pawl 19 is 95 adapted to be swung back, up and out of the way, see Figure 2, as occasion may require.

What I claim is:—

1. In a power operated swinging wringer, 100 means to automatically lock the wringer frame against movement in one direction while permitting a free swinging movement in the other direction; said locking means being arranged to be released by a free manual manipulation in any position of the frame without the use of tools, to permit swinging movement in either direction, and means pivoted on said locking means for locking said frame, when adjusted, against movement in either direction.

110 2. In a power operated swinging wringer, in combination, a support, a wringer frame swingable on said support, a ratchet toothed member fixed on said support having peripherally arranged radially disposed teeth, a housing connected to said frame and having a depending annular flange overlying and embracing said member and an opening in said flange, a pawl pivoted within said housing to be moved horizontally into and out of engagement with the teeth on said member and yieldingly held in contact with the teeth of said member and having a finger-hold portion projecting through the opening in said flange.

120 3. In a power operated swinging wringer, in combination, a support, a wringer frame swingable on said support, a ratchet toothed member fixed on said support having radially disposed teeth, a housing connected to 130

said frame and having a depending annular flange to embrace said member and an opening in said flange, a pawl pivoted within said housing and yieldingly held in contact with the teeth of said member and having a finger-hold portion projecting through the opening in said flange and a locking member pivot-

ally connected with said finger-hold movable to engage with the wall of the opening in said flange.

In witness whereof, I have hereunto affixed my hand this 28th day of April, 1923.

10

ALPHEUS W. ALTORFER.
